(57) **CLAIM**

The ornamental design for a two hole faucet, as shown and
described.

DESCRIPTION

FIG. 1 is a front perspective view of a two hole faucet, showing
the new design;

FIG. 2 is a front view of the two hole faucet;

FIG. 3 is a rear view of the two hole faucet;

FIG. 4 is a side view of the two hole faucet;

FIG. 5 is another side view of the two hole faucet;

FIG. 6 is a top view of the two hole faucet; and,

FIG. 7 is a bottom view of the two hole faucet.

The broken lines showing various elements of the two hole
faucet are included for the purpose of illustrating non-
claimed subject matter and form no part of the claimed
design.
